UNITED STATES PATENT OFFICE.

GEORGE A. HARPER, OF BURLINGTON, WISCONSIN, ASSIGNOR TO BURLINGTON BRASS WORKS, OF BURLINGTON, WISCONSIN, A CORPORATION OF WISCONSIN.

DESIGN FOR A FAUCET.

Application filed January 26, 1925. Serial No. 12,155. Term of patent 7 years.

To all whom it may concern:

Be it known that I, GEORGE A. HARPER, a citizen of the United States, residing at Burlington, in the county of Racine and State of Wisconsin, have invented a new, original, and ornamental Design for Faucets, of which the following is a specification, reference being had to the accompanying drawings, forming a part thereof.

The figure of the drawings is a front elevation showing my new, original, and ornamental design for faucets.

What I claim is:—

The ornamental design for a faucet substantially as shown.

In witness whereof I hereto affix my signature.

GEORGE A. HARPER.
